James Wager, of Troy, N.Y.
Letters Patent No. 735. Dated Oct. 16, 1855.

The schedule referred to in this Letters Patent, and making part of this

To all whom it may concern,

Be it known that I, James Wager, of Troy, in the County of Rensselaer, & State of New York, have invented or produced a new & original design for a Cook Stove, which I call the "Merit," & I do hereby declare that the following is a full, clear, & exact description of the same, reference being had to the annexed perspective drawing, & to the letters of reference marked thereon, making part of this specification.

My design of Cook Stove, is as follows, viz: A, is the bottom plate, having an ornamental moulding B, around its edge, C, is the jamb plate, with the oven doors D.D', and fire door E; the doors have the ornamental moulding F, at their edges, & upon their panels are the ornaments G, G', A. H, is the front plate with the large damper doors H, at bottom, and small ones J.J' at top; the large doors have ornamental mouldings K, for their borders and ornaments L, on their panels. The smaller doors have the ornamental moulding M, for their edges, & the ornamental work N, on

their panels. O, is the top plate with the zig-zag moulding P, around its edge, Q, is the leg ornamented with the spiral ribs R,

Having described my design of Cook Stove, What I claim as new & desire to secure by Letters Patent, is the ornamental design & configuration of Cook Stove plates, such as herein described and shown in the annexed drawing.
